UNITED STATES PATENT OFFICE

JAMES E. BURNS, OF BRIDGEPORT, CONNECTICUT, ASSIGNOR TO REMINGTON ARMS COMPANY, INC., A CORPORATION OF DELAWARE

AMMUNITION

No Drawing.

Application filed August 27, 1930. Serial No. 478,294.

This invention relates to priming mixtures for ammunition, and particularly to priming mixtures of the non-corrosive type, such mixtures being characterized by the absence of any ingredients which leave hygroscopic residues in the gun bore, thereby promoting corrosion and rusting of the bore. A few such mixtures are known at this time and owing to their highly desirable non-corrosive properties they have largely displaced the older corrosive mixtures.

The function of a priming mixture being to supply a flame of sufficient intensity and heat to ignite propellant powder, the priming compositions include two essential ingredients; first, a fuel or substance to be burned, and second, an oxidizer to furnish oxygen for the combustion of the fuel. A third ingredient, however, is quite universally used, the function of which, stated in very general terms, is to initiate the reaction between the oxidizer and the fuel; thus, its essential characteristic is that it react under the stimulus of a blow to produce sufficient flame and/or heat to start the combustion of the fuel by the oxidizer. As such a combustion initiator mercury fulminate has been very extensively used for a long period of time. Mercury fulminate, however, is undesirable for several reasons. It is expensive and dangerous to manufacture, and great difficulty is encountered in securing a product of uniform quality. Indeed the variation in the quality of different lots of mercury fulminate has but recently been fully recognized, and it is now thought to be responsible for variations in quality of different lots of ammunition which have hitherto been considered inevitable and unexplainable. Further, mercury fulminate is of a poisonous character and injurious to the health of the workmen who handle it or priming mixtures containing it. Further, it amalgamates with the metal of cartridge cases and primer cups rendering it incapable of use in primer cups and (rim fire) shells of such alloys as brass, which are otherwise highly desirable for this purpose.

The present invention contemplates a priming mixture which is not only non-corrosive but in which undesirable mercury ful-

minate has been replaced by materials which, while fully efficient as combustion initiators, can be safely made of uniform quality, are non-poisonous and easily handled, and permit the use for primer cups and rim fire shells of metals and alloys, such as brass, which are attacked by mercury fulminate. It has been discovered that by the use of a mixture of two explosive organic materials, neither of which is by itself entirely suitable for this purpose, a very effective combustion initiator for primers is secured.

Certain organic nitro compounds have been proposed as substitutes for mercury fulminate, and used with a measure of success, particularly in detonators, in which a detonation producing shock rather than a combustion initiating flame is desired. It has now been discovered that greatly improved combustion initiation is secured by the use together of two different organic nitro compounds, such for example as a nitrated quinone-di-azide and a metallic salt of one of the nitro derivatives of resorcine. More particularly, a very desirable combustion initiator comprises the 4-6-dinitro-quinone-2-diazide, $C_6H_2N_4O_5$, frequently called "diazodinitrophenol"; and the normal lead salt of trinitroresorcine, $C_6H(NO_2)_3O_2Pb$. These materials may be used in conjunction with one or more oxidizers, such as barium nitrate, lead nitrate, lead peroxide, etc.; and one or more fuels, such as lead sulphocyanate, antimony sulphide and calcium silicide. Typical mixtures are

	Per cent	Per cent	Per cent
Diazodinitrophenol	2	4	6
Lead trinitroresorcinate	40	40	38
Lead nitrate	30	30	30
Lead sulphocyanate	8	7	7 90
Glass	20	18	18
Gum		1	1

The glass may be omitted if the fuel or the characteristics of a particular cartridge render it unnecessary.

Applicant being the first to utilize an admixture of materials of the type set forth as a combustion initiator, the appended claims are to be broadly construed.

What is claimed is:

1. A priming mixture comprising diazo-dinitrophenol and lead trinitroresorcinate.
2. A priming mixture comprising diazo-dinitrophenol, lead trinitroresorcinate, an oxidizer, and a fuel.
3. A priming mixture comprising diazo-dinitrophenol, lead trinitroresorcinate, lead nitrate, and lead sulphocyanate.
- 10 4. A priming mixture comprising substantially:

	Per cent
Diazodinitrophenol approximately	6
Lead trinitroresorcinate "	38
15 Lead nitrate "	30
Lead sulphocyanate "	7
Glass "	18
Gum "	1
